UNITED STATES PATENT OFFICE.

WILLIAM H. SOMMER, OF PEORIA, ILLINOIS.

HOT TOP FOR INGOT MOLDS.

Application filed November 21, 1923. Serial No. 676,186.

To all whom it may concern:

Be it known that I, WILLIAM H. SOMMER, a citizen of the United States, residing at Peoria, in the county of Peoria and State 5 of Illinois, have invented certain new and useful Improvements in Hot Tops for Ingot Molds, of which the following is a specification.

This invention has reference to hot-tops 10 for ingot-molds.

The principal object of the invention is the use of my improved hot-top for ingot-molds, to prevent or reduce the formation of the pipe or shrinkage cavity that occurs 15 in ingots during solidification or freezing.

The invention has for a further object to provide for ingots-molds, a hot-top to act as a reservoir for an excess supply of molten metal, so that during the solidification or 20 freezing of the ingot, and in the event of a pipe, or shrinkage cavity forming in the ingot during solidification, such molten metal in the hot-top will run into and fill the pipe or cavity being formed.

A further object of the invention is to provide a hot-top for ingot-molds which is preferably made in the form of a hollow flanged member into which a suitable molding sand, or refractory material may 30 be tamped, and leaving a central opening therethru, preferably of the same cross-section as the top of the mold, whereby, whatever solidified metal is left in the hot-top when the mold is stripped from the ingot a larger yield may be obtained, without 35 subsequent loss by cropping.

That the invention may be more fully understood reference is had to the accompanying drawing forming a part of the description, illustrating a preferred embodiment of the invention in which:—

Fig. 1 shows by dotted lines a common form of ingot-mold and stool and in cross-section my improved hot-top thereon;

Fig. 2 is a plan view of Fig. 1;

Fig. 3 is a view similar to Fig. 1 except the mold is of the inverted type;

Fig. 4 is a plan view of Fig. 3;

Fig. 5 is a detail view on a larger scale showing in cross-section my improved hot-top, and

Fig. 6 is a plan view of my hot-top.

Like characters of reference denote corresponding parts thruout the figures.

In Figs. 1 and 2 I have shown in dotted lines the usual ingot-mold 1 and a stool 2,

and in Figs. 3 and 4 I have also shown in dotted lines an inverted mold 3 and stool 4. In each instance my improved hot-top is applied thereto. . . . .

60

My improved hot-top, designated 5, is preferably a hollow flanged member, which in contour preferably conforms to the contour of the mold on which it is to rest. The flanged portion of the hot-top resembles a channel with a top flange 6 of greater width than the lower flange 7, and in said channel is tamped or otherwise packed, suitable molding sand 8, or other suitable refractory material. When the material 8 is tamped 70 into the channel of the hot-top it is also packed around the peripheral face of the flange 7, and an opening 9 is formed thru the hot-top which in cross-section is the cross-section of the width of the opening 75 formed by the flange 6, which also corresponds in cross-section to the opening in the mold at the top thereof. Making the opening formed by the flange 7 larger than the flange 6, and filling the space 80 between the flange 7 and the inner wall of the opening 9 thru the hot-top with molding sand, or suitable refractory material, when the hot-top is placed on the top of the mold, the opening in the top of the mold will be surrounded by the sand or refractory material, as shown in Figs. 1 and 3. This will prevent the molten metal being poured into the mold from passing out between the hot-top and the top of the mold. In view of 90 the fact that the end of the ingot-mold is usually rough, the top surface of the mold is covered with a suitable loam making it possible to obtain a snug fit of the hot-top on the end of the mold.

95

Assuming the mold being in position to receive molten metal from a ladle or other pouring means and the hot-top is in position on the top of the mold, the pouring continues until the hot-top is filled, or partially filled, 100 with the molten metal. The sand or refractory material in the hot-top acts as an insulator and will keep the metal in the hot-top in a molten state much longer than would the ingot-mold, and in the event of a pipe or cavity forming in the ingot, the metal in the hot-top, which is in a molten state, will run into and fill the pipe or cavity forming in said mold. In many instances very little of the metal in the hot-top will flow or run into the mold, because 105 of the lack of pipe or cavity forming, and

110

the cross-section of the metal in the hot-top finally solidifying or freezing being of the same cross-section as the top of the ingot, it will be apparent that it may be rolled with the body of the ingot and thus save considerable cropping or discard.

The outer wall of the hot-top is provided with a plurality of vent holes 10 for the escape of any gases accumulating in the hot-top.

What I claim is:—

1. A hot-top for ingot-molds, comprising a channeled body formed by inturned top and bottom flange, the flanges at the top end being of greater width than at the bottom end, and an insulating filling for said body with an opening therethru, in cross-section corresponding to the opening thru the top of said flanges and with the opening at the top of said mold.

2. A hot-top for ingot-molds, comprising a channeled body formed by inturned top and bottom flange, the flange at one end being of greater width than at the other end, and an insulating filling for said body with an opening therethru corresponding to the opening thru the flange having the greatest width, said filling also being packed in front of the peripheral face of the narrow flange and forming a facing together with said flanges for one end of said body.

3. A hot-top for ingot-molds, comprising a body formed with an opening therethru the cross-section of which is the same as the cross-section of the opening in the top of the mold, and also provided with an interiorly arranged channel conforming to the contour of said body, the outer wall of the channel being provided with vent openings, and an insulating filling in said channel having an opening therethru corresponding to the opening thru said body.

4. A hot-top for ingot-molds, comprising a body formed with a channeled interior and an opening therethru the cross-section of which is substantially the same as the

cross-section of the opening in the top of the mold, and means for venting the channel.

5. A hot-top for ingot-molds, comprising a body formed with a channeled interior produced by top and bottom flanges, said flanges each having openings therethru, the bottom flange enclosing an area of larger cross-section than that enclosed by the top flange.

6. A hot-top for ingot-molds, comprising a body formed with a channeled interior produced by top and bottom flanges, said flanges each having openings therethru, the area enclosed by the bottom flange of greater cross-section than that enclosed by the top flange, and an insulating filling packed in said body between said flanges and having an opening therethru corresponding, in cross-section, to the opening thru the top of said flanges and with the opening at the top of said mold.

7. A hot-top for ingot-molds, comprising a body formed with a channeled interior produced by top and bottom flanges, said flanges each having openings therethru, one having a larger cross-section than the other, and the opening thru one of said flanges in cross-section being the same as the cross-section of the opening in the top of the mold.

8. A hot-top for ingot-molds, comprising a body formed with a channeled interior produced by top and bottom flanges, said flanges each having openings therethru, the opening in the top flange having a larger cross-section than the lower and corresponding to the cross-section of the opening at the top of the mold, and an insulating filling packed in said body between said flanges and partially filling the opening formed by the lower flange, so as to provide an insulator for a part of the end of the body intended to rest on the mold.

Signed at Peoria, in the county of Peoria and State of Illinois, this 14th day of November, A. D. 1923.

WILLIAM H. SOMMER.
